UNITED STATES PATENT OFFICE.

JOHN G. CAPSTAFF, OF ROCHESTER, NEW YORK, ASSIGNOR TO EASTMAN KODAK COMPANY, OF ROCHESTER, NEW YORK, A CORPORATION OF NEW YORK.

DRIER FOR MOTION-PICTURE FILMS.

1,394,249.

Specification of Letters Patent.

Patented Oct. 18, 1921.

Original application filed March 29, 1918, Serial No. 225,388. Divided and this application filed April 2, 1920. Serial No. 370,847.

To all whom it may concern:

Be it known that I, JOHN G. CAPSTAFF, of Rochester, in the county of Monroe and State of New York, have invented certain new and useful Improvements in Driers for Motion-Picture Films; and I do hereby declare the following to be a full, clear, and exact description of the same, reference being had to the accompanying drawings, forming a part of this specification, and to the reference-numerals marked thereon.

My present invention relates to drying apparatus and more particularly to machines for drying continuous flexible strips. This application is a division of my prior pending application Serial No. 225,388, filed March 29, 1918, and entitled "Apparatus for treating motion picture film." This invention has for its object to provide an improved drier of considerable capacity and in a convenient form that will be adapted for drying motion picture film in strips after the film has passed through a dyeing process for the projection of pictures in color, though the present apparatus in some of its aspects, has a wider range of usefulness that will be recognized by those skilled in the art. To these and other ends the invention resides in certain improvements and combinations of parts all as will be herein-after more fully described, the novel features being pointed out in the claim at the end of the specification.

In the drawings:

Figure 1 is a side elevation of a drier constructed in accordance with and illustrating one embodiment of my invention, the same being shown in connection with a fragment of the dyeing apparatus claimed in my said parent application and in connection with which the present drier is adapted to work to perform a continuous dyeing and drying operation upon the film;

Fig. 2 is a top plan view and

Fig. 3 is an enlarged section taken substantially on the line 3-3 of Fig. 1.

Similar reference numerals throughout the several views indicate the same parts.

In certain processes of color photography as applied to motion pictures, two colors are used in the film, one red and the other green and they are applied to opposite faces of the film strip in a liquid state by the machine, a fragment of which is shown at the right

of Figs. 1 and 2. The film is indicated at A 55 and after receiving the dye on its under side only, it passes out of the container 6 beneath an idler 23 and thence over two capillary rolls 24 that similarly treat only the under side and apply a mordanting solution. The 60 film strip then passes beneath an idler 26 and over a device indicated generally at 29 that involves a vacuum tube 30 and which removes excess liquid from the under surface of the film.

The film having been dyed, mordanted and the excess liquid removed from its surface, it is passed into the drying chamber of the present invention embodying a casing 37 having an entrance slot 38. At the top 70 of this drying chamber are a plurality of roller supports 39 and there is a similar series 40 at the bottom. The film strip first passes over a roll 41 adjacent to the slot 38 and thence downwardly under the first of 75 the roller supports 40, thence upwardly over the first of the roller supports 39 and so back and forth so that it is disposed in vertical loops until it finally emerges at the last roll 39 which is in a wall of the casing 37 whereupon the strip passes downwardly and is wound upon a take-up roll 42 supported in brackets 43 on the exterior of casing 37. This roll is driven by a belt 44 passing over a pulley 45 thereon and thence over a pulley 46 on the casing 37, which pulley 46 is in turn driven, in the present instance, by a belt 47 running to a pulley 48 on a shaft 49 forming part of certain gearing embodied in the dyeing machine. The mordanting rolls 90 24 are positively driven from the same source of power and in a direction that assists the passage of the film strip through the machine. Otherwise, the strip is drawn through the machine by the take-up roll 42.

Extending from the top of the casing 37 are a plurality of partitions 56 which meet the roll supports 40 and come on opposite sides of the roll supports 39 while from the bottom of the casing extend upwardly a plurality of partitions 57 which terminate short of these roll supports 39 and come on opposite sides of the roll supports 40. In other words, the partitions 56 inclose the downwardly opening loops of the film 36 while the partitions 57 extend within these loops. A suitable blower 58 impels a current of air against the treated side of the film as it enters the

drying chamber and this air current follows the sinuous passage formed by the partitions 56 and 57 in which the film is disposed, finally emerging through an exhaust opening 59 at the opposite side of the dry chamber, all as will be observed from an inspection of Fig. 1. It will be noted in this connection, that the current of air when so directed follows along in contact with the treated face of the film rather than the untreated face, passing between the partitions 57 and the roll supports 39 but under the roll supports 40.

The casing 37 has been shown, in the present instance with a glass front 60

through which the progress of the film may be observed.

I claim as my invention:

In a machine for treating continuous lengths of motion picture film, a drier comprising a casing and upper and lower guides therein over which the film may be passed in successive loops, partitions connecting one set of guides with the opposite wall of the casing and alternating partitions having their ends spaced from the other set of guides to form a sinuous passage for the film and means for moving a current of air through said passage on one side of the film.

JOHN G. CAPSTAFF.
